UNITED STATES PATENT OFFICE

JOHN E. SHUTT, OF STUTTGART, ARKANSAS

DEEP-WELL PUMP

Application filed September 27, 1928. Serial No. 308,604.

This invention relates to improvements in deep well pumps and especially relates to deep well pumps of the cylinder and piston type, which employ fluid columns in place of the ordinary piston rod.

In deep well pumps, especially those used in the oil fields where depth is often excessive, it is quite common for the well to be deflected in drilling from the vertical, 10 in which case the casing is at times so crooked that it is necessary to abandon the hole entirely, or, where it can be used, excessive friction of the pump rod is set up, and owing to bucking of the rod, the full 15 stroke of the pump is not always obtained. In addition where the depth is great, the weight of the pump rod is so great that it must be made of excessive cross section in the upper portion of the well and great 20 difficulty is had in balancing this weight in an endeavor to keep down operation cost. Such pumps also where they have to be pulled for cleaning or repairs require not only that the discharge pipe carrying the 25 cylinder be removed but they also require in addition that the pump rod be first removed. With these facts in view the objects of my invention are:

(a) To substitute for the piston rod a balanced liquid column, which column does not require a straight hole, eliminates the effect of depth, and reduces frictional resistance and buckling, thereby reducing the power required to raise the oil or other 35 liquid pumped; and eliminates the necessity of pulling a pump rod in taking out the pump for cleaning;

(b) To eliminate or substantially reduce trouble caused by sand;

(c) To eliminate pounding from gas where gas bearing oil is being pumped;

(d) To reduce the number of parts which must be carried in stock for substitutions where paraffin clogging is encountered and

45 where consequently it is necessary to remove the pumping parts and either hold the well open until the paraffin can be removed or else substitute parts in order that immediate replacement may be made;

50 (e) To provide means for separating the

pumping column from the liquid to be pumped; and

(f) To generally improve the design and construction of such pumps.

The means by which the foregoing and other objects are accomplished, and the manner of their accomplishment will readily be understood from the following specification, on reference to the accompanying drawing, in which:

55 Fig. 1, is a sectional elevation, on the center line of the well, disclosing a single acting pump construction and indicating a means by which the water column may be actuated;

60 Fig. 2, is a similar sectional elevation showing a double acting pump; in both views details of construction being largely omitted;

65 Fig. 3, is an enlarged view of the pumping mechanism outlined in Fig. 1, showing details of construction, the view being reduced in vertical height in order that the details may be shown on a larger scale;

70 Fig. 4, is a similarly enlarged section taken on the line IV—IV of Fig. 3;

75 Fig. 5, is a similarly enlarged and vertically condensed section showing the detail of construction of the double acting pump outlined in Fig. 2.

80 Referring now to the drawing in which the various parts are indicated by numerals, 10 is an outer or well casing which extends from the surface of the ground to the bottom of the well. 11, is an inner casing which extends downward from the surface of the ground within the well casing 10, and 12 is the discharge pipe through which the oil or other liquid pumped is delivered above the ground surface.

85 Secured to and supported by the casing 11, is a power cylinder 13, within which power cylinder is a reciprocable power piston 14. Secured to and extending below the power cylinder is a pump cylinder 15, in which pump cylinder is a pump plunger 16. The pump plunger 16, is connected to the power piston 14, by a piston pipe 17, which serves also as a portion of the discharge pipe.

The lower end of the inner casing 11, is connected to the upper end of the power cylinder 13, by a fitting 18, having a plurality of passage-ways 19, therethrough, which passage-ways establish uninterrupted connection between the interior of the inner casing and the interior of the power cylinder so that the column of fluid within the annular chamber lying between the exterior of the discharge pipe 12 and the interior of the inner casing 11, is in direct communication with the upper face of the piston 14. The fitting 18, is likewise provided with a central bore 20, which establishes communication between the piston pipe 17, and the discharge pipe 12.

Surrounding the bore 20 at the upper end thereof is an annular seat 21, which is adapted to receive, and form a water tight joint with, the lower end of a ball cage 22, which is secured to the lower end of the discharge pipe 12. The seal thus effected, completes the annular chamber surrounding the discharge pipe and within the inner casing. Preferably the joint between the seat and the ball cage is a ground joint. Disposed within the cage 22, is an annular valve seat 23 for a ball valve 24, this annular seat preferably being exteriorly tapered and removably seated against the correspondingly tapered inner portion of the cage 22. The ball valve assembly will be hereinafter referred to as the discharge-pipe check valve, and the cage 22, therefor, will be referred to as the discharge-pipe check valve cage.

Disposed in and forming a part of the outer casing 10, is a fitting 25, which is provided with an annular seat 26, which is adapted to receive the lower end of a fitting 27, which fitting is secured to and forms a bottom end of the power cylinder 13. The joint between the fitting 27 and the seat 26 is preferably a ground joint so that when the inner casing 11 is lowered, the power cylinder 13 is supported by, and sealed off from, the bottom of the well by this joint. The seal thus effected, completes an annular chamber surrounding the inner casing and within the well casing. The fitting 27 serves also to connect the power cylinder 13 and the pump cylinder 15. At the lower end of the pump cylinder 15 is a ball valve 28, which serves as a check valve for the lower end of the pump cylinder.

29 indicates a reciprocating pump from one end of which pump a pipe 30 connects into the annular chamber between the inner casing 11 and the outer casing 10 and 31 is a similar pipe connecting from the other end of the pump cylinder into the annular chamber within the inner casing which surrounds the discharge pipe 12.

Referring now to Figs. 1, 3 and 4, the 65 single acting pump plunger 16 comprises an annular casting 32, the upper end of which is tapped out and screwed on to the lower end of the piston pipe 17. The lower end of the casting 32 is interiorly threaded to receive a second annular casting 33, which casting is provided with an annular seat 32 on which a ball check 35 is normally seated. The casting 33, is provided with piston rings 36 or other packings which form a tight seal between the plunger and the cylinder. The upper portion of the casting 32 is preferably provided with an annular extension 37 having a groove 38 therearound, with openings 39 leading inward from the bottom of the groove into the annular space 40, which surrounds the piston pipe 17, this space forming a pocket to receive and hold sand which may have worked past the piston or otherwise have been trapped thereabove. Passage-ways 41 lead through the walls of the cylinder 15 above the plunger to prevent trapping of oil or gas in the upper end of the cylinder.

The fitting 27 is interiorly threaded to receive the lower end of the power cylinder 13, and similarly threaded to receive the upper end of the pump cylinder 15. It is provided with a stuffing box which surrounds the piston pipe 17 in which stuffing box, packing 42 is disposed, this packing being compressed by a gland 43 which is held in place and tightened by a cover 44. The fitting 27 and this stuffing box form the lower end of the power cylinder 13. Communication is established into this portion of the cylinder through passage-ways 45 which lead from the annular chamber between the well casing 10 and the inner casing 11.

The piston 14, which is integral with the piston pipe 17, is preferably provided with piston rings 46, and with annular skirts 47 and 48, which are provided with sand grooves 49 and 50 respectively. From the sand grooves 50 passage-ways lead inward into the annular space between the skirt 48 and the power cylinder 13 to permit any sand trapped by the groove 50 being carried into this space.

Depending from the fitting 18, is a sleeve 52, the upper end of which is threaded into the fitting and the lower end of which is provided with a stuffing box in which packing 53 is disposed. 54 is the stuffing box gland and 55 the cover therefor. The upper end of the piston pipe 17 is provided with a sand groove 56, from which passage-ways 57 lead into the pipe.

Referring now to Figs. 2 and 5 the double acting plunger 16, comprises an integral casting which is interiorly threaded and screwed on the lower end of the piston pipe 17. Projecting laterally from this casting, are annular flanges 58, 59, the latter of which is annular and preferably interiorly threaded so that it may be removed and re-

placed. 60 is a lock nut. 61 are passages leading laterally from the interior to the exterior of this plunger between the flanges 58 and 59. 62 is a floating ring, closely fitting the interior of the pumping cylinder 15, which ring is provided with a plurality of piston rings 63, or other packing. The interior portion of the ring 62 is beveled on opposite sides, and the flanges 58 and 59 are correspondingly beveled, so that when the flange 59 comes against the lower surface of the ring 62, it seats thereagainst in the manner of a poppet valve at the same time the flange 58 is held away from the opposite side of the ring 62 establishing thereby a passage-way through the channel ways 61 from the upper end of the pump cylinder into the discharge pipe 17, whereas when the flange 58 seats against the upper surface of the ring 62 a closure is similarly formed against such part and the flange 59 is held away from the opposite side of the ring establishing a similar passage-way from the lower end of the cylinder into the discharge pipe.

The fitting 27 for convenience of construction is preferably made up of a central portion which is exteriorly threaded to receive an annular member 64, into the upper portion of which the inner casing 13 is screwed. The lower portion of this annular member is shaped to conform to the seat 26, the joint therebetween preferably as before stated being a ground joint. The upper portion of the fitting 27 is provided with a stuffing box, in which is disposed packing 65 which surrounds the piston pipe and is held in place by a gland 66 and tightened by a cover 67. The lower portion of this fitting is chambered out to form an annular chamber 68, within which chamber is disposed a member 69 having its outer surface a truncated cone, the conical surface of which is held against a corresponding conical surface on the interior of the fitting 27, by a compression spring 70. 71 are passage-ways leading through the fitting 27, which passage-ways are normally closed by the member 69, but which passage-ways are opened on the down stroke of the pump plunger to permit inflow of liquid to the pumping cylinder. The power piston 14, is provided with piston rings 72, and with cup leathers 73 which may be held in place by rings 74, and cap screws 75. This piston 14, is provided with a stuffing box surrounding a pipe 76 which is screwed into and depends from the fitting 18, this pipe forming a portion of the discharge line. This stuffing box is provided with packing 77, held in place by a gland 78 and a cover 79. A cup leather 80 may additionally be used should it be so desired and if used, this cup leather may be held in place by a cover 81 screwed over the cover 79 or in some other desired man-

ner. Screwed into and depending from the piston 14, is a pipe 82, the lower end of which is screwed into a fitting 83 into which fitting in turn the piston pipe 17 is screwed, these two pipes in effect forming the piston pipe.

In installing the pump, the well casing 10 carrying the fitting 25 in the lower end thereof, is first placed, or if a casing is already in the well without such fitting, any of the ordinary forms of "packers" may be lowered and placed in the casing near the bottom of the well and secured in the casing in the usual manner in place of this fitting. The inner casing 11 carrying the power cylinder 13 and the pump cylinder 15 may then be lowered into the well and seated on this fitting or on the packer as the case may be. Thereafter the discharge pipe 12 is lowered to place and seated on the seat 21, of the fitting 18, at the lower end of the casing 11. The pump 29 may then be connected up by the pipe 30 to the well casing, and by the pipe 31 to the inner casing and the well caps 84 and 85 be put in place. No special detail is shown for these above-ground connections, as they may be of any usual or well known type. The annular chambers between the well and inner casing, and between the inner casing and discharge pipe, are then filled with some liquid, ordinarily water.

In using the pump, the forward and backward strokes of the pump 29 alternately force liquid into the inner and outer chambers and the pressure thus induced alternately acts upon the top and the bottom of the power piston 14 to force the same downward and then upward. On the down stroke, referring first to the single acting pump shown in Fig. 1, oil or other liquid to be pumped, which has entered the bottom of the pumping cylinder 15 through the ball valve 28, passes upward through the check valve 32 into the piston pipe 17. On the up stroke this liquid is forced upward through the discharge check valve into the discharge pipe 12 and additional liquid is at the same time drawn through the valve 28 into the lower end of the pumping cylinder. As pumping is continued, the liquid thus pumped is discharged through the pipe 12 above the surface of the ground.

In the double acting pump, oil or other liquid to be pumped, trapped by the check valve 28, on the down stroke of the plunger flows past the flange 59 and through the passages 61 into the piston pipe 17. At the same time liquid is drawn into the upper portion of the cylinder through the passage-ways in the check valve 69. On the up stroke, liquid within the upper portion of the cylinder is forced past the flange 58 and through the passages 61 into the piston pipe 17, and an additional charge is drawn

through the check valve 28 into the bottom of the pumping cylinder. Liquid thus forced into the piston pipe is forced upward through the discharge line check valve 5 into the discharge line and thence, on continuation of pumping, to the surface.

In either case should there be gas in the liquid it will largely be forced through the discharge check valve into the discharge 10 pipe and such small amount be left below as to eliminate trouble from gas pounding, which is always present where a long column of gas bearing liquid rests directly on the pump plunger.

15 Should sand be encountered, it will be forced during pumping above the discharge pipe check valve and during pumping will be kept so thoroughly agitated as to cause little trouble. On shutting down the pump 20 however, this sand will settle and may accumulate in such quantity as to block the use of the pump. In such extreme cases it is only necessary to pull the discharge line, unscrew the discharge check valve and clean 25 out the accumulated sand, a proposition involving little trouble as compared to the corresponding trouble where a rod is used to operate the pump piston.

Should paraffin trouble occur it will ordinarily clog up the discharge pipe. In such case it is only necessary to pull the discharge pipe, remove the check valve therefrom, replace sections of discharge pipe seriously clogged, and replace the check valve, after 30 which the discharge pipe may be replaced in the well without serious loss of time. Should however, the trouble be more serious, the entire inner casing may be removed with little trouble and such pump parts as are 35 clogged up be taken off for cleaning, additional ones substituted, and the pump again put in use without serious delay. In any of these operations, it will be noted that there is no piston rod to be pulled out before 40 the discharge and other pipes can be removed. It will also be noted that raising of either the discharge pipe or the inner casing instantly releases the liquid in the surrounding chamber so that only the weight of the 45 discharge pipe, or the casing as the case may be, must be contended with. It will further be noted that the water columns used in pumping are balanced so that the effect of the weight thereof and therefore of the 50 depth of the well is not felt on the piston and that neither of the water columns is in communication with the liquid which is being pumped.

Having described my invention, what I 55 claim is:

1. In a deep well pump, a well casing, an inner casing within said well casing, and a discharge pipe within said inner casing, means for sealing the lower end of said pipe 60 to said inner casing, and the end of said

inner casing to said well casing to define annular chambers, a power cylinder, having its upper end in communication with the inner of said annular chambers, and its lower end in communication with the outer of said chambers, a piston in said power cylinder, a pump cylinder secured to said power cylinder, a plunger in said pump cylinder connected with said power piston, said power piston and connection having a 70 passage-way therethrough communicating with said discharge pipe, a check valve in the lower end of said pump cylinder, a check valve in the lower end of said discharge pipe, and means for alternating pulsation of liquid columns in said annular chambers to reciprocate said power piston.

2. In a deep well pump, a well casing, an inner casing within said well casing, and a discharge pipe within said inner casing, means for sealing the lower ends of said inner casing and pipe to define annular chambers therearound, a power cylinder, having its upper end in communication with the inner of said annular chambers, and its lower end in communication with the outer of said chambers, a piston in said power cylinder, a pump cylinder secured to said power cylinder, a plunger in said pump cylinder connected with said power piston, said power piston and connection having a 80 passage-way therethrough communicating with said discharge pipe, a check valve in the lower end of said pump cylinder, and means for alternating pulsations of liquid 85 columns in said annular chambers to reciprocate said power piston.

3. In a deep well pump, a well casing, an inner casing within said well casing, means sealing the lower end of said inner casing to said outer casing and a discharge pipe within said inner casing, removably seated and sealed at its lower end to said inner casing, said sealing defining annular chambers, a power cylinder, having its upper end in direct communication with the inner of said annular chambers, and its lower end in communication with the outer of said chambers, a piston in said power cylinder, a pumping cylinder secured to said power cylinder, a piston in said pumping cylinder connected with said power piston, said power piston and connection having a passage-way therethrough communicating with said discharge pipe, a check valve in the lower end of said pump cylinder, a check valve in the lower end of said discharge pipe, and means for 90 alternating pulsations of liquid columns in said annular chambers to reciprocate said power piston.

4. In a deep well pump, a well casing, an inner casing within said well casing, removably seated and sealed at its lower end to said well casing, and a discharge pipe with- 100

in said inner casing, seated and sealed at its lower end to said inner casing, said seals defining annular chambers, a power cylinder, having its upper end in direct communication with the inner of said annular chambers, and its lower end in communication with the outer of said chambers, a piston in said power cylinder, a pump cylinder secured to said power cylinder, a piston in said pumping cylinder connected with said power piston, said power piston and connection having a passage-way therethrough communicating with said discharge pipe, a check valve in the lower end of said pump cylinder, a check valve in the lower end of said discharge pipe, and means for alternating pulsations of liquid columns in said annular chambers to reciprocate said power piston.

5. In a deep well pump, a well casing having an annular seat near the lower end thereof, an inner casing disposed within said outer casing, an annular fitting, including an annular seat on the lower end of said inner casing, a power cylinder carried by and depending below said fitting, an annular fitting forming the lower end of said cylinder, shaped to conform with said well casing seat, to form a support for said cylinder and inner casing and to form a seal defining an annular chamber between said inner casing and said well casing, a discharge pipe within said inner casing, a check valve on the lower end of said discharge pipe, said valve having its lower end shaped to conform with said inner casing seat to form a support for said discharge pipe and to form a seat defining an annular chamber between said discharge pipe and inner casing; a pump cylinder secured to and depending from said cylinder fitting, a check valve at the lower end of said pump cylinder, a piston in said power cylinder, a plunger in said pump cylinder, a check valve in said plunger; an integral piston-pipe connecting said piston and plunger, and projecting above said piston, a stuffing box surrounding said piston-pipe above said piston and a stuffing box surrounding said piston-pipe between said piston and plunger; and means for alternating pulsations of liquid columns in said annular chambers to reciprocate said piston.

6. In a deep well pump, a well casing having an annular seat near the lower end thereof, an inner casing disposed within said outer casing, an annular fitting, including an annular seat on the lower end of said inner casing, a power cylinder carried by and depending below said fitting, an annular fitting forming the lower end of said cylinder, shaped to conform with said well casing seat, to form a support for said cylinder and inner casing and to form a seal defining an annular chamber between said inner

casing and said well casing, a discharge pipe within said inner casing, having its lower end shaped to conform with said inner casing seat to form a support for said discharge pipe and to form a seat defining an annular chamber between said discharge pipe and inner casing, a pump cylinder secured to and depending from said cylinder fitting, a check valve at the lower end of said pump cylinder, a piston in said power cylinder, a plunger in said pump cylinder, a check valve in said plunger; an integral piston-pipe connecting said piston and plunger and projecting above said piston, a stuffing box surrounding said piston-pipe above said piston and a stuffing box surrounding said piston-pipe between said piston and plunger; and means for alternating pulsations of liquid columns in said annular chambers to reciprocate said piston. 70
75
80
85
90
95
100
105
110
115

7. In a deep well pump, a well casing having an annular seat near the lower end thereof, an inner casing disposed within said outer casing, an annular fitting, including an annular seat on the lower end of said inner casing, a power cylinder carried by and depending below said fitting, said cylinder having its lower end shaped to conform with said well casing seat, to form a support for said cylinder and inner casing and to form a seal defining an annular chamber between said inner casing and said well casing, a discharge pipe within said inner casing, a check valve on the lower end of said discharge pipe, said valve having its lower end shaped to conform with said inner casing seat to form a support for said discharge pipe and to form a seat defining an annular chamber between said discharge pipe and inner casing, a pump cylinder secured to and depending from said power cylinder, a check valve at the lower end of said pump cylinder, a piston in said power cylinder, a plunger in said pump cylinder, a check valve in said plunger; an integral piston-pipe connecting said piston and plunger and projecting above said piston, a stuffing box surrounding said piston pipe above said power piston and a stuffing box surrounding said piston pipe between said pistons, and means for alternating pulsations of liquid columns in said annular chambers to reciprocate said piston. 120
125

8. A deep well pump, comprising a well casing, an annular seat within and integral with said casing, an inner casing, a power cylinder and a pump cylinder carried by said inner casing, a ring surrounding said inner cylinders and secured thereto, adapted to rest on said seat to support said inner casing and seal off said well casing below said seat, said power cylinder being above said ring, and having its upper end in communication with said inner casing, and said 120

inner casing having openings therethrough into the bottom end of said power cylinder whereby communication is established between said cylinder and well casing, a piston 5 ton in said power cylinder, and a plunger, secured to and actuated thereby, in said pump cylinder, a discharge pipe within said inner casing, communicating with said pump cylinder and sealed from said power cylinder and means for establishing alternate pulsations of liquid columns within 10 said casings.

9. A deep well pump, comprising a well casing, an inner casing, a power cylinder 15 and a pump cylinder carried by said inner casing, means for supporting said cylinders and inner casing within said well casing, said means sealing off said well casing therebelow, said power cylinder having its upper 20 end in communication with said inner casing, and said inner casing having openings therethrough at the bottom end of said power cylinder whereby communication is established between said cylinder and well 25 casing, a piston in said power cylinder, and a plunger, secured to and actuated thereby, in said pump cylinder, a discharge pipe within said inner casing, communicating with said pump cylinder and sealed from 30 said power cylinder and means for establishing alternate pulsations of liquid columns within said casings.

10. A pump having three annular nested casings, establishing annular passageways 35 and a central discharge column, a power cylinder and a pump cylinder carried by one of said casings, a hollow piston rod disposed in said cylinders, a piston carried by said rod and reciprocably disposed in said power 40 cylinder, a stuffing box above and a stuffing box below said piston, the upper and lower ends of said power cylinder communicating respectively with the inner and outer of said annular passageways, a hollow plunger 45 secured to the lower end of said hollow rod and reciprocably disposed in said pump cylinder and a valve in said hollow piston.

11. A deep well pump, comprising a well casing, an inner casing within said well casing, and a discharge pipe within said inner casing, defining segregated annular chambers, and a central discharge column, a power cylinder and a pump cylinder carried by said inner casing, said power cylinder 55 having its upper end in communication with said inner casing, and its lower end in communication with said well casing, a piston in said power cylinder, and a plunger, connected to said piston, disposed in said pump cylinder, said piston, plunger and connection having a passageway therethrough establishing communication from said pump cylinder to said discharge column, a check valve in 60 the lower end of said pump cylinder, and 65

means for establishing alternate pulsations of liquid columns within said casings.

In testimony whereof I hereunto affix my signature.
